UNITED STATES PATENT OFFICE.

DAVID P. WOLHAUPTER, OF WASHINGTON, DISTRICT OF COLUMBIA.

ELECTRICAL PULL-SOCKET.

1,001,330.

Specification of Letters Patent. Patented Aug. 22, 1911.

Application filed January 28, 1911. Serial No. 605,209.

To all whom it may concern:

Be it known that I, DAVID P. WOLHAUPTER, a citizen of the United States, residing at Washington, District of Columbia, have 5 invented certain new and useful Improvements in Electrical Pull-Sockets, of which the following is a specification.

This invention relates to electrical pull sockets of that type wherein a pull chain or 10 equivalent flexible pull connection is employed for operating the socket switch to make and break the electrical circuit through the incandescent lamp.

To this end the present invention contemplates certain novel and practical improvements which greatly simplify the construction and manufacture of electrical pull sockets, particularly with respect to reducing the number of operating parts and the 20 ease and certainty with which such parts may be readily assembled and also disassembled.

A further object of the invention is to provide an improved construction of pull 25 socket which entirely dispenses with the ratchet commutator so commonly employed and which commutator involves the idea of ratchet inclines either on the porcelain of the socket body or on a rotating member, 30 said inclines alternately presenting metal contact faces and insulating faces that provide for the make and break of the circuit. In place thereof, the present invention proposes to utilize a plain metal switch of a 35 simple type, but preferably having a snapping action to secure a quick-break of the circuit, in combination with a simple form of ratchet operating mechanism, and an insulator between the two, which insulator is 40 not only utilized to transmit motion to the switch parts, but also acts as a complete insulating cover for the switch so as to provide a socket wherein there may be said to be a perfect insulation for the parts of 45 opposite polarity so that there is no danger of short circuiting from stray ends of wires at the wire terminals or from other causes. Besides, this idea of insulation, as claimed herein, admits of direct metallic connection 50 between the pull chain and the pull lever of the operating mechanism.

I do not confine myself, in carrying out the above objects, to the precise details of construction of the various parts of the 55 socket, but preferred and practical embodi-

ments thereof are shown in the accompanying drawings, in which—

Figure 1 is a longitudinal sectional view of a pull socket embodying the present invention. Fig. 2 is a cross sectional view on the line 2—2 of Fig. 1. Fig. 3 is a similar view on the line 3—3 of Fig. 1, and illustrating the switch closed, on one-quarter turn of the switch block. Fig. 4 is a view similar to Fig. 3 showing the other quarter turn of the block, wherein the circuit is opened by a quick break. Fig. 5 is a sectional view showing a modification in the switch. Fig. 6 is a sectional view on the line 6—6 of Fig. 5, showing the switch open. Fig. 7 is a perspective view showing the simple manner of assembling the switch operating mechanism with the rotating switch block and the interposed insulator; the view illustrating the several parts in separated relation.

Like references designate corresponding parts in the several figures of the drawings.

A pull socket, constructed in accordance with the present invention, includes in its organization the usual external socket casing C, the interior insulating socket body, the socket switch, and the switch operating mechanism. The particular construction of the socket insulating body is unimportant except as to the provision for housing the switch and insulating it from the operating mechanism and the wire terminals. Hence, for illustrative purposes there is shown the conventional form of socket body consisting of two suitably connected blocks A and B of porcelain or equivalent insulating material. The socket switch may be conveniently located within a housing chamber 1 recessed into the inner side of one of the insulating blocks, which may be the lower block B shown in the drawings, and as above indicated is intended to be completely insulated from its operating mechanism and from the terminal plates to which the wire ends are connected.

The switch proper which is preferably arranged as stated, may consist of any simple type of all metal snap switch as distinguished from a switch of the ratchet commutator type, but for purposes of illustration, there is shown in the drawings, in one embodiment, a quick-break snap switch consisting of a spring contact plate 2, and a rotary contact member 3, the latter being in

the form of an oblong switch block similar to the corresponding block employed in the well known key sockets now on the market. The said switch block 3 is intended to be 5 loosely mounted upon a center supporting spindle 4 extending centrally through the blocks of the socket body and, in the form of the invention being described, acting as a center conducting screw which holds in place 10 the center plug contact 5 arranged at the under side of the lower block B. Hence, in this form, the spindle 4 acts as a conductor so that current passes through the same and the rotary member or switch block 3. When 15 the latter is in contact with the spring contact plate 2, the switch parts are placed in electrical and metallic connection with one of the wire terminal plates 6 which may be used as a uniting plate between the two insulating blocks, while the other wire terminal plate 7 performs a similar office and furthermore has a direct metallic screw connection 8 with the screw shell contact 9, all 20 of which plainly appears in Fig. 1 of the drawings.

The snapping action of the loose member or switch block 3 is effected by means of a spring pressed snapper plate 10, held under the influence of the press spring 10^a against the switch block 3 at all times, and the pressure of this plate is exerted in line with the center of the axis for the switch block so that at each quarter turn of the block the element 10 acts as a detent therefor while the ratchet 35 operating mechanism is resuming a fresh-starting position, as will be well understood by those skilled in the art. At the same time, as the ends of the block 3 commence to pass off of the plates 2 and 10, the latter plate takes up the movement and quickly snaps the block around to the position shown in Fig. 4, thus securing the quick-break.

The operating mechanism for the switch 45 consists of a rotating ratchet member or disk 11, an oscillating ratchet member or pull lever 12, and a pull chain 13. The ratchet member 11 may consist of a disk in ring form having punched out or equivalent 50 ratchet shoulders 14, and punched out or equivalent holding elements 15, the latter being separably interlocked in sockets or depressions 16 in the insulator 17 that is interposed between the switch parts and the said 55 operating mechanism. This insulator may conveniently consist of a disk of insulating material which is mounted to turn freely on the spindle 4 and carries with it the switch block 3. Any suitable separable connection 60 may be provided between the switch block and the insulator, such for instance as holding 65 projections 19 on the switch block separably interlocking in sockets or depressions 20 provided in the insulator 17.

65 The insulator or insulating disk 17, in the

form being described, is provided with an insulating hub 21 which extends through the operating mechanism and effectually insulates all metal parts from the center supporting spindle 4. Furthermore, the said 70 insulator is arranged so as to wholly cover the housing chamber 1 and the switch therein, besides being so located as to constitute an effective separator between all opposite polarity parts.

75 The ratchet elements or shoulders 14 of the ratchet member 11 are adapted to be engaged successively by the pawl or equivalent ratchet element 22 of the ratchet part of the pull lever 12, and the latter is also provided with a chain holder or clip 23 to which is directly connected the metallic pull chain 13 that is guided to the exterior of the casing through the usual chain guide 24.

80 The pull lever 12 is normally retracted under the impulse of a retracting spring 25, one end of which as at 26, engages with the pull lever or its ratchet part, and the other end of which spring is engaged in any one of a series of holes or equivalent keepers 27 90 provided in a tension washer 28. This washer is of an angular form and is loosely seated in a correspondingly shaped seat 29 provided in the under side of the insulating block A. The tension of the spring 25 may 95 be increased or diminished as desired by either changing the position of one end thereof to the proper keeper 27 of the washer 28 or by turning the latter one way or the other, to the extent desired, and then dropping it back into its seat 29 in which it is held interlocked with the angular faces of the latter. The extent of movement of the pull lever in both directions may be definitely determined by the simple use of a stop 100 pin 30 mounted in the socket body and engaging in a limiting slot 31 provided in the hub or other convenient part of the pull lever member.

105 A modification of the invention is suggested in Figs. 5 and 6 of the drawings, wherein the switch proper is shown as consisting of the snapper plate 10 and a spring contact plate 2^a, the latter being adapted 110 to be engaged and disengaged by the snapper plate to close and open the circuit, and the switch block 3^a being an integral or rigid part of the insulator 17^a. In this form of the invention the insulator does not require the hub 21, as the center plug contact of the socket has a direct metallic connection with one of the wire terminal plates X, while, as shown, the switch 2^a and 10 is included in the opposite side of the circuit 115 with the other wire terminal plate 7 and 120 with the screw shell contact 9. In other respects, the modification described possesses all of the desirable features hereinbefore specified.

125 In the operation of the socket, it will be 130

observed that the insulator 17 acts as a transmitter of motion from the ratchet operating mechanism to the switch elements for opening and closing the circuit, while 5 at the same time performing its insulating office as hereinbefore referred to. Mention has already been made of the successive quarter turns of the switch block to first open and then close the circuit, and with the 10 snapper plate 9 acting as a detent, the parts 11, 17 and 3 are held stationary while the pull lever 12 is retracted through its idle movement by the spring 25. On its forward movement the pull lever 12 moves through 15 a quarter circle, determined by the stop 30-31, and in such movement engages the ratchet elements 14 to rotate the member 11 and the parts connected therewith. During the forward movement of the pull lever 20 when the snapping action of the switch block takes place, the parts 3, 17 and 11 simply snap ahead of the pull lever till brought to a stop by the switch block reaching the position shown in Fig. 4.

25 I claim:

1. A pull socket comprising a chambered body, a switch arranged within the chamber of the body, metallic operating means including a pull chain, and an insulator interposed between the operating means and switch and arranged to cover the latter in its chamber.

2. A pull socket comprising an insulating body, a stationary center spindle fitted in the body, a snap switch seated within the body and including a rectangular switch block loosely mounted on the spindle and freely rotatable about the same, snapping

means for the switch block, metallic operating means for turning the switch block 40 independent of the spindle on which it is supported, and insulating means for the metallic operating means.

3. A pull socket comprising a chambered insulating body, a stationary center spindle 45 fitted within the body, a snap switch seated within the chamber of the body and including a rectangular switch block and snapping means therefor, said switch block being loosely mounted on the spindle and freely 50 rotatable on and about the same, and operating means for the switch including a pull chain.

4. A pull socket comprising a chambered body, a snap-switch seated within the chamber of the body and including a rotary rectangular switch block and snapping means therefor, metallic operating means including a pull chain, and an insulator arranged as a cover for the switch and interposed between the latter and the operating means.

5. A pull socket comprising a chambered body, a snap-switch seated in the chamber of the body and including a rotary rectangular switch block and snapping means therefor, an insulator arranged at one side of the switch block and connected therewith, said insulator acting as a switch cover and having a hub, and metallic operating means 65 pivotedly hung upon said hub.

In testimony whereof I hereunto affix my signature in the presence of two witnesses.

DAVID P. WOLHAUPTER.
